UNITED STATES PATENT OFFICE.

PHILIP BUCK, OF RUGBY, TENNESSEE.

BOTTLE AND LAMP-CHIMNEY CLEANER.

973,911.

Specification of Letters Patent. Patented Oct. 25, 1910.

Application filed January 3, 1910. Serial No. 535,917.

To all whom it may concern:

Be it known that I, PHILIP BUCK, a citizen of the United States, residing at Rugby, in the county of Morgan and State 5 of Tennessee, have invented certain new and useful Improvements in Bottle and Lamp-Chimney Cleaners, of which the following is a specification.

This invention relates to lamp chimney 10 and bottle cleaners, and is designed particularly to construct an article of this type and character which will be adapted to cleanse all curves and crevices occurring in bottles and jars.

With the above and other objects in view 15 this invention consists of the construction, combination and arrangement of parts all as hereinafter more fully described, claimed and illustrated in the accompanying drawings, wherein:

Figure 1 is a perspective view of a device constructed in accordance with the present invention; Fig. 2 is a vertical section partly 20 in elevation of a cleanser operating in a bottle or jar.

The cleaner forming the subject-matter 25 of the present invention resides in the provision of a pair of arms connected at their upper extremities by a coil, said arms and coil being constructed of spring metal in such a manner that the former are adapted 30 to diverge at their lower extremities. One of said arms carries a brush adjustable to various angles to the vertical and horizontal, 35 while the other is provided with a vertical brush adapted to bear against the sides of a bottle. To further provide for the cleansing of the bottle a scraper is carried on the coil and is suspended between the arms.

A continuous piece of wire 1 forms the 40 main body portion of this invention and has the centrally disposed coil 2 formed therein nearer one extremity than the other, forming the arms 3 and 4, the arm 4 as a result 45 of the location of the coil 2 being considerably shorter than the arm 3. A small inner coil 5 is formed on the lower side of the coil 2 and in said coil is secured a rod which provides a means of securing one extremity 50 of one of the brushes to the said coil 2.

The lower extremity of the arm 3 is bent 55 outwardly at 6 and then downwardly, said downwardly bent portion being contained in the upper extremity of the back of the brush 7, being retained therein by the staple 8 spanning said bent portion 6. The brush 7

is adapted to remain permanently in a vertical position, bearing outwardly against the sides of the bottle or chimney indicated in general as A.

The lower extremity of the arm 4 is provided with a pair of superposed loops 9 and 10, said loop 10 being at the extreme terminal of the arm, and extends inwardly toward the arm 3, the opening therein being 60 aligned with the opening in the loop 9.

An extension rod 11 is mounted in the lower extremity of the arm 4, and is adapted to reciprocate thereon. At the upper extremity of the rod 11 are a pair of superposed loops 12 and 13, said loops extending outwardly and having the openings thereof coinciding and adapted to engage the lower terminal of the arm 4. In order to limit the reciprocation of the rod on the arm 4, the 70 loop 13 operates between the loops 9 and 10 of the arm while the loop 12 at the extremity of the rod 11 engages the arm 4 above the loop 9. The space between the loops 12 and 13 is curved inwardly toward the arm 3 in 80 such a manner that the passage of the same exerts a pressure against the loop 9 of the arm and forms a means whereby the rod may be retained at any locality within the limit of its reciprocation.

The lower extremity of the rod 11 is bent 85 outwardly at 14 and pivotally engages at the outer extremity of said portion the back of the brush 15 by having the loop 16 passing through an opening adjacent the extremity 90 of the brush and countersunk in the recess 17 in the extremity of the brush. At the opposite extremity of the brush there is secured a ring 18 to which is attached the rod 19, said rod being bent to supply a substantial 95 clearance for the arm 4 and its extension 11. At the upper extremity this rod is passed through the loop 5 and is bent upon itself engaging the main body portion thereof, after which it is given a twist about the 100 arm 4.

Detachably secured to the main body of the coil 2 is a scraper indicated in general as B, comprising a handle rod 20, the upper extremity of which is bent upon itself and 105 has a hook 21 formed thereon to engage the shank 20, thus supplying a means whereby the scraper may be attached to the rod. At the lower extremity of the shank 20 is the angularly bent portion 22, on which is permanently attached the scraper 23.

From the foregoing it will be seen,

through the reciprocation of the extension 11 of the arm 4, the brush 15 is adjustable to various angles and may be retained therein through the instrumentality of the pressure exerted between the curved portion between the loops 12 and 13 of the rod 11, and the loop 9 formed at the lower terminal of the arm 4.

The entire construction, being of spring wire, the arms are diverging and consequently are adapted to bear against the sides of the average size bottle or jar and exert a sufficient pressure thereagainst to thoroughly cleanse the same.

15 Should any dirt or foreign matter become caked or dried in the bottle, the scraper B is brought to operate against the same, removing it sufficiently to permit the brushes to cleanse the bottle by ordinary methods.

20 The brush 7 is of a much larger size than the brush 15, due to the fact that it remains permanently in vertical position while the brush 15 is adjustable to various positions and is adapted to reach any corners and

25 crevices of bottles, jars or lamp chimneys.

Having thus described my invention, what is claimed as new is:

1. An article of manufacture comprising a portion of spring wire coiled adjacent one

extremity thereof, a vertical brush carried at one extremity of said wire and an adjustable brush at the other, and means for removing hardened dirt.

2. A device of the class described comprising spring wire arms resiliently connected, having brushes secured to their extremities, one of said brushes being vertical and the other adjustable to various angles, means whereby said adjustable brush may be retained in any desired position, and means whereby hardened dirt may be removed.

3. An article of manufacture comprising a plurality of resiliently connected arms, one of said arms carrying a vertical brush, an auxiliary arm slidably mounted on the remaining arm, a brush having one extremity secured to said auxiliary arm, and a supporting arm interposed between the free terminal of the brush and the resilient connection between the main arms aforesaid.

In testimony whereof I affix my signature in presence of two witnesses.

PHILIP BUCK.
